United States Patent Office

Des. 203,514

Patented Jan. 18, 1966

203,514

SELF-PROPELLED COTTON HARVESTER

Perry M. Roberson and Harold K. Garrison, Newton,
and Richard E. Ten Eyck, Wichita, Kans., assignors to
Hesston Manufacturing Company, Inc., Hesston, Kans.,
a corporation of Kansas

Filed Jan. 28, 1965, Ser. No. 83,617

Term of patent 14 years

(Cl. D40—1)

Des. 203,514

PAGE 2

Fig. 2.

Fig. 3.

FIG. 1 is a left front perspective view.

FIG. 2 is a front perspective view.

FIG. 3 is a rear perspective view.

FIG. 4 is a perspective view showing the right hand side opposite to the side illustrated in FIG. 1.

The dominant features of our design reside in the portions shown in full lines.

We claim:

The ornamental design for a self-propelled cotton harvester, substantially as shown and described.
